UNITED STATES PATENT OFFICE.

CHARLES BOOZ, OF BUFFALO, NEW YORK, ASSIGNOR TO HENRY M. BIRGE, OF SAME PLACE.

DESIGN FOR WALL-PAPER.

SPECIFICATION forming part of Design No. 26,140, dated September 29, 1896.

Application filed August 24, 1896. Serial No. 603,799. Term of patent 31 years.

To all whom it may concern:

Be it known that I, CHARLES Booz, a citizen of the United States, residing at Buffalo, in the county of Erie and State of New York, have invented and produced a new and original Design for Wall-Paper, of which the following is a specification, reference being had to the accompanying drawing, showing a part thereof.

10 The design consists of an arrangement of ornamental scrolls forming a series of concentric panels, with groups of flowers and leaves in the center panels, as represented in the accompanying drawing. Sprays of flowers and leaves and ornamental scrolls also connect said panels, as shown in the drawing.

15 The border for this design consists of ornmental scrolls forming concentric panels, with groups of flowers and leaves in the center panels and ornamental scrolls and sprays of flowers and leaves connecting said panels, as shown in the drawing.

What I claim is—

1. The design for wall-paper herein shown and described.
2. In the design for wall-paper the border herein shown and described.

Witness my hand this 10th day of August, 1896.

CHARLES BOOZ.
